[57] CLAIM

The ornamental design for an elastomeric shoesole, as shown and described.

DESCRIPTION

FIG. 1 is a top and left rear perspective view of an elastomeric shoesole showing my new design;

FIG. 2 is a top and right rear perspective view thereof; FIG. 3 is a side elevational view thereof as seen from the side shown in FIG. 1;

FIG. 4 is a cross-sectional view transversely thereof through one of the triangular cutouts;

FIG. 5 is a bottom plan view thereof; and

FIG. 6 is a top and left rear perspective view of another embodiment of my new design of FIGS. 1 to 3, the opposite side and bottom being identical with FIGS. 2 and 3.

FIG. 1
